Ben H. Morse, INVENTOR

BY *Victor J. Evans*
ATTORNEY

WITNESS

Legislature,

UNITED STATES PATENT OFFICE

BEN H. MORSE, OF HILSDALE, MICHIGAN

BURIAL VAULT

Application filed September 21, 1931. Serial No. 564,098.

The invention relates to a burial vault and more especially to an interliner for burial vaults.

The primary object of the invention is the provision of a vault of this character, wherein an interliner fits within the same so that an air chamber or space is provided about the sides and top of the vault interiorly thereof, thus permitting any moisture entering the vault through the walls or from condensation due to decomposition of the body or otherwise to escape from between the walls of the interliner and the walls of the vault and to be drained away through drainage openings in the bottom or base of such vault.

Another object of the invention is the provision of a vault of this character wherein the construction thereof is novel in form so that in event that there should be excessive moisture collecting within the vault the air within the interliner will exclude such water from rising to the level of the casket resting within the vault, thus keeping the same at all times dry and in good condition.

A further object of the invention is the provision of a vault of this character which is extremely simple in construction, thoroughly reliable and efficient in its purpose, neat and attractive in appearance, strong, durable, and inexpensive to manufacture.

With these and other objects in view, the invention consists in the features of construction, combination and arrangement of parts as will be hereinafter more fully described in detail, illustrated in the accompanying drawings, which discloses the preferred embodiment of the invention, and pointed out in the claims herunto appended.

In the accompanying drawings:—

Figure 1 is a vertical longitudinal sectional view through a vault constructed in accordance with the invention showing the interliner therein and this section being taken approximately on the line 2—2 of Figure 2.

Figure 2 is a top plan view showing the cover or lid of the vault removed.

Figure 3 is a sectional view on the line 3—3 of Figure 1 looking in the direction of the arrows.

Similar reference characters indicate cor-

responding parts throughout the several views in the drawings.

Referring to the drawings in detail the vault comprises a body 5 having an open top and such body is molded or otherwise formed from concrete or the like although other similar and analogous materials might be used. The body throughout the bottom 6, sides 7 and ends 8 has embedded therein metallic reinforcement 9 to give strength and durability thereto.

Formed in the open top about the side and ends 7 and 8 of the body 5 is a seat 10 to accommodate the rim 11 of a lid or cover 12, the latter being made from concrete or other like material and is preferably upwardly arched in cross section, the rim 11 being adapted to fit within the seat 10 in the open top of the body 5 and is sealed thereto through the medium of a filler 13 poured about the lid or cover 12 into the seat 10 in the body 5 as is clearly shown in Figures 1 and 3 of the drawings.

The bottom 6 of the body 5 is preferably raised to provide interiorly of said body a rest slab 15 about which is marginally formed a continuous channel or groove 15 which is entirely about the ends and sides of said slab and into which is introduced an interliner 16 preferably made from sheet copper, the interliner being of a size when its free edge rests within the channel or groove 15 to effect an air space or chamber 17 entirely about the sides, ends and top of the vault, that is to say the space or chamber being formed between the outer surface of the interliner 16 and the confronting surfaces of the sides, ends and top cover or lid of the vault.

The groove or channel 15 beyond the ends of the slab 14 has intersecting the same spaced holes or passages 18 these opening through the bottom 6 of the body 5 and constitute vents for the escape of moisture, water or condensation from within the vault as may accumulate within the interliner 16 or the air space or chamber 17 hereinbefore described. The interliner 16 is fitted into the vault in such a manner that there is a continuous air space or chamber 17 between the sides, ends and top of the interliner and the sides, ends

and top of the vault, thus permitting any moisture entering into the vault through the walls thereof or from condensation due to decomposition of the body or otherwise to escape from between the walls of the interliner 5 and the walls of the vault into the channel or groove 15 in which the interliner rests and to drain away or off through the holes or passages 18 outside of the vault.

10 The edge of the interliner 16 resting within the continuous channel or groove 15 will enable moisture collecting within the channel or groove from rising to the level of the casket placed above the slab 14 upon raised 15 lugs 19, thus keeping the said casket dry at all times and in good condition and the air within the interliner will exclude water from entering the holes or passages 18 from without the vault.

20 What is claimed is:—

21 1. The combination of a vault having a removable lid, a slab elevated from the bottom of the vault and forming a continuous channel about said slab, said vault having openings in its bottom intersecting the channel, and an interliner within the vault and spaced therefrom to provide an air space between it and the walls of the vault.

22 2. The combination of a vault having a removable lid, a slab elevated from the bottom of the vault and forming a continuous channel about said slab, said vault having openings in its bottom intersecting the channel, an interliner within the vault and spaced therefrom to provide an air space between it and the walls of the vault, and rests formed on the slab and adapted to elevate a casket therefrom.

In testimony whereof I affix my signature.

40 BEN H. MORSE.
